CLAIM

The ornamental design for a adjustable spray can holder for spraying at high positions, as shown and described.

DESCRIPTION

FIG. 1 is a front elevational view of the adjustable spray can holder tool for spraying at high positions showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The cross-hatched shading on the straps represents conventional woven material and is understood to cover the entire surface.
